US00D441457S

(12) **United States Design Patent** (10) Patent No.: **US D441,457 S**
Neiner et al. (45) Date of Patent: ** May 1, 2001

(54) **STERILIZATION CASSETTE**

(75) Inventors: **Karen L. Neiner, Chicago; Matiwala R. Ongchangco, Streamwood; Larry E. Smith, Chicago, all of IL (US)**

(73) Assignee: **Hu-Friedy Mfg. Co., Inc., Chicago, IL (US)**

(**) Term: **14 Years**

(21) Appl. No.: **29/121,281**

(22) Filed: **Apr. 4, 2000**

(51) LOC (7) Cl. **24-01**

(52) U.S. Cl. **D24/217**

(58) Field of Search **D24/217; 422/300, 422/297; 206/370, 366, 363, 439, 318**

(57) **CLAIM**

The ornamental design for a sterilization cassette, substantially as shown and described.

DESCRIPTION

FIG. 1 is a perspective view of a cassette in accordance with the present invention;

FIG. 2 is a front elevational view of the cassette of FIG. 1; FIG. 3 is a side elevational view of one end of the cassette of FIG. 1, the other end being identical;

FIG. 4 is a top plan view of the cassette of FIG. 1;

FIG. 5 is a rear elevational view of the cassette of FIG. 1;

FIG. 6 is bottom plan view of the cassette of FIG. 1;

FIG. 7 is a perspective view of the cassette of FIG. 1 in an open state with a first orientation;

FIG. 8 is a perspective view of the cassette of FIG. 1 in an open state with the second orientation;

FIG. 9 is a perspective view of an alternate embodiment of a cassette in accordance with the present invention;

FIG. 10 is a front elevational view of the cassette of FIG. 9; and,

FIG. 11 is a perspective view of the cassette of FIG. 9 in an open state.

The side, top, rear and bottom views of the cassette of FIG. 9 are identical to those of the cassette of FIG. 1.
